TRANSDUCER SYSTEM

Harry J. Woll, Indianapolis, Ind., assignor to
Radio Corporation of America, a corporation of
Delaware

Application December 1, 1944, Serial No. 566,143

3 Claims. (Cl. 178—160.4)

1

My present invention relates generally to an improved balanced transducer system, and more particularly to a novel system for deriving from small variations of electrical capacity into correspondingly relatively large variations of direct current or potential.

In his application Serial No. 490,614, filed June 12, 1943, U. S. Patent No. 2,371,373, issued March 13, 1945, A. Badmaieff has disclosed and claimed a method of, and means for, using a balanced transducer for concurrently varying the frequency of a source of oscillations and a discriminator resonant frequency in opposite senses thereby to provide cancellation of even harmonics, greatly to reduce distortion and to double the discriminator output voltage. More specifically, Badmaieff disclosed an embodiment wherein a push-pull form of condenser pickup concurrently, but in opposite senses, varied the frequency of the oscillator tank circuit of a multi-grid tube and the frequency of a discriminator circuit located in the plate circuit of the multi-grid tube. He utilized a rectifier to derive from the plate circuit a voltage representative of the pick-up capacity variations.

It is one of the important objects of my present invention to provide a more compact system having operational advantages similar to those of the Badmaieff system, but eliminating the need for a special rectifier.

Another important object of my invention is to assign a double function to the oscillator grid circuit of the aforesaid multi-grid tube; the oscillator grid circuit in my invention acting to provide grid-leak detection whereby the plate circuit has current flowing therethrough containing an audio frequency component.

Another, and more specific, object of this present invention is to provide a multi-grid tube having a cathode and two cold electrodes adapted to function as a generator of high frequency oscillations, whereas a cold output electrode is provided with a resonant circuit mistuned from the oscillator circuit by a predetermined amount, and a balanced reactive transducer being employed to vary the frequencies of the oscillator circuit and resonant output circuit whereby the latter develops a voltage whose magnitude and phase are dependent upon the oscillator frequency and the resonant output circuit frequency.

Still other objects of my invention are to improve the simplicity, efficiency and reliability of record reproduction systems of the frequency modulation (FM) type, and more especially to

2

provide a high fidelity, low cost and low distortion record reproducer system.

Still other features of my invention will best be understood by reference to the following description, taken in connection with the drawing, in which I have indicated diagrammatically a circuit organization whereby my invention may be carried into effect.

In the drawing:

10 Fig. 1 shows an embodiment of my invention; and

Fig. 2 shows an ideal resonance curve of the resonant plate circuit.

Reference is made to the aforesaid Badmaieff patent for a detailed explanation of the advantages of utilizing the balanced form of transducer for concurrent variation of oscillator tuning and discriminator tuning in opposite phase relation. While the system disclosed herein is described in connection with record reproduction, it is to be clearly understood that it may be used for record cutting, measurement devices, where linearity and small pickup area are desired, such as for pressure measurement, liquid height measurement, elongation measurement, vibration measurement. Where the pickup device is a microphone, the system could be used for hearing-aid apparatus, public address systems, binaural systems and the like.

20 The pickup device may be constructed in the manner shown by Badmaieff in his aforesaid patent, or it may be constructed in any other suitable manner to provide push-pull reactance changes. The pickup is, therefore, schematically represented as comprising a pair of spaced fixed electrodes 1 and 2. Midway between the stators 1 and 2 is located a mobile electrode 3 provided with a record-scanning stylus. The circuit operatively associated with the pickup device will now be described.

25 The tube 4 in Fig. 1 is shown as of the pentode type, although any other type tube may be used. Its cathode 5 is connected to a low alternating potential tap 6 on the oscillator coil L1. The coil 45 L1 is preferably of the variable inductance type, and has an adjustable core of comminuted iron. The core is schematically shown. The control grid 7, which functions as the oscillator section grid, is connected through the direct current blocking condenser 8 to the high alternating potential side of coil L1 and to fixed plate 1 of the balanced capacity pickup device. The mobile element 3 of the pickup device is connected by lead 9 to the negative terminal —B, which may be ground, of the direct current energizing source.

The positive terminal +B of the source may be at +300 volts. The positive terminal +B is connected through resistor 9' to the cold electrode 10 of multi-grid tube 4.

Electrode 10 functions as the oscillator anode of the tube. The output electrode or plate 11 has one connection through the direct current blocking condenser 12 to the fixed plate or stator 2 of the balanced capacity pickup device. A second conductor connects plate 11 to the high alternating potential end of the discriminator coil L2 in accordance with my invention. The coil L2 is, also, a variable inductance having a core of comminuted iron, and the low potential end of coil L2 is connected to the +B terminal through output load resistor 13. The third or suppressor grid 14 of tube 4 may be connected to grounded lead 9. A suitable bypass condenser 9'' is connected to ground from the energizing lead feeding the anode 10 and plate 11. Condenser 10' connects the junction of coil L2 and resistor 13 to ground. Condenser 10' establishes the lower end of coil L2 at ground potential for high frequency currents, and has a relatively high impedance to audio frequency currents.

The cathode 5, grid 7 and electrode 10 of tube 4 provide the oscillator section of the system. The positive cold electrode 10 is connected to the lower end of coil L1 through direct current blocking condenser 15. Electrode 10 is, therefore, the oscillator anode. Coil L1 is resonated to a mean, or center, frequency F_c . This mean frequency is to be deviated in accordance with the amplitude of the modulation frequencies. The mean frequency of the oscillator may be chosen from a range of 20 to 60 megacycles (mc.). The deviation range of the mean frequency is dependent on the capacity change and the mean frequency employed. A deviation up to about 1% of the mean frequency could be employed, but it should be noted that this total deviation is the sum of the oscillator deviation and the discriminator resonance peak deviation. The choice of the mean frequency of the oscillator is dependent on the sensitivity that is required from the pickup device. Since the capacity change, due to vibration, is of constant range as compared to the amount of deflection, then the higher the frequency the more this given capacity change will produce a frequency swing. Therefore, the mean frequency should be as high as possible, and yet not too high to be unstable. In other words, the distributed capacity of the coils is likely to be less at the higher frequencies. My invention is entirely independent of specific frequencies disclosed herein.

It will be understood that in accordance with my present method the condenser 1, 3 is connected across the oscillator coil L1, while the condenser 3, 2 is shunted across the discriminator coil L2. The discriminator coil should be slightly off tune from the oscillator mean frequency F_c , either above or below. For example, the oscillator mean frequency, as shown in Fig. 2, may be below the discriminator coil peak resonance frequency. The amount of off tune depends on the "Q" of the discriminator resonance, which is the slope of the two sides of the peak. The oscillator mean frequency F_c should be located at a fairly linear part of the discriminator curve side. The maximum frequency deviation could be as high as 120 kilocycles (kc.) on either side of F_c . The generic expression "angle modulated" is used herein to designate that the modulation of the high frequency oscillations may

either be in frequency or phase. Preferably, it is desirable to adjust the iron core of coil L2 so that the peak frequency of the discriminator circuit is of a value such that the mean oscillator frequency F_c falls at approximately 70% of the response on one side of the resonance curve characteristic of the discriminator circuit. Specifically, and merely by way of illustration, F_c could be 26 mc., while the plate coil L2 could be normally tuned to 26.1 mc.

The oscillator grid condenser 8 is shunted by grid leak resistor 16 thereby providing the means for grid-leak detection at the oscillator grid. The numeral 17 indicates a coupling path from the plate circuit of tube 4 to the oscillator grid circuit. The coupling means may be an external reactance, or it may be provided by the distributed capacity between the pickup plates 1 and 2 as well as the inter-electrode capacity within the tube.

In general, the operation of the system is such as to develop across load resistor 13 a signal voltage representative of the displacement of electrode 3. Where the latter is actuated by a stylus scanning the grooves of a sound record, there will be developed across resistor 13 amplified audio frequency voltage corresponding to the recorded sound. Variation of capacities of condensers 1, 3 and 3, 2 changes the tuning of the tuned circuits L1—1, 3 and L2—2, 3 with respect to each other. If the plate circuit L2—2, 3 and oscillator grid circuit L1—1, 3 were tuned to a common frequency, plate voltage would be fed back to grid 7 in phase quadrature with the oscillator grid voltage. The feedback occurs, of course, through path 17. If, however, the two resonant circuits are not tuned to a common frequency, the plate voltage will be fed back to oscillator grid 7 at a phase angle greater or less than 90 degrees depending on the sense of detuning. As a result of this feedback voltage the oscillator voltage will be dependent upon the relative tunings of the two resonant circuits. Since the oscillator grid bias depends upon the amplitude of oscillations, the plate current of tube 4 is also dependent on the relative detuning of the two tuned circuits. Hence, the variable plate current develops a variable voltage across resistor 13 which is a measure of the motion of mobile electrode 3.

While the invention is in no way limited or restricted to actual constants, the following are supplied by way of illustration:

Resistance of resistor 16=18,000 ohms
Resistance of resistor 9'=47,000 ohms
Resistance of resistor 13=100,000 ohms
Capacity of condenser 8=27 micro microfarads
(mmf.)

Capacity of condenser 15=120 mmf.

Capacity of condenser 10'=33 mmf.

Inductance of coil L1=20 turns at 30 mc.

Inductance of coil L2=20 turns at 30 mc.

Considering more specifically the electrical relations existing in the present system, it is pointed out that the locally-produced oscillations of 26 mc. are both frequency modulated and amplitude modulated. In my present system I utilize the fact that due to the non-linear action of the oscillator, the plate current of tube 4 will contain an audio frequency component. It is the voltage fed back through coupling path 17 which amplitude modulates the high frequency oscillations. However, it is the frequency modulating of the oscillations which causes the plate circuit L2—2,

3 to develop a voltage whose magnitude and phase are variable and depend on the oscillator frequency. The oscillator section excites the plate resonant circuit by virtue of electron coupling within the tube. When the high frequency plate current flows through its resonant circuit, the voltage developed thereacross depends upon what the oscillator frequency is at that moment with respect to the frequency of resonance of the resonant plate circuit. It will be obvious, therefore, that wide changes in phase and magnitude of the high frequency plate voltage will be developed because of the push-pull detuning of the oscillator tank circuit and the plate resonant circuit. As the mobile electrode 3 moves in one direction the frequency of oscillation is varied. Concurrently the frequency of the plate resonant circuit is changed in an opposite sense thereby causing the high frequency voltage across L2 to change to a degree determined by both of the 20 said changes.

Since there exists coupling between the two resonant circuits (and this coupling may be capacitative, inductive, resistive or space charge) voltage is fed back from coil L2 to the oscillator 25 grid 7. There is, therefore, produced a secondary change in oscillator frequency and amplitude due to this feedback voltage. This secondary change in amplitude of oscillation affects the plate current flow in the tube, and produces an audio frequency voltage across the load resistor 13. It may, also, be said that the leaky grid condenser network in the circuit of the oscillator grid functions to provide grid-leak detection of amplitude modulated oscillations. At the same time the 35 tube acts as a pentode amplifier for the audio frequency voltage developed across resistor 13, and which voltage was caused by the changes in plate current due to the variations in oscillator grid bias which was in turn caused by the feedback voltage.

The feedback through capacity 17 changes the amplitude of radio frequency oscillation at an audio frequency rate. This is amplitude modulation. Because the amplitude of the radio frequency oscillation changes at an audio rate, the grid current, and hence the grid voltage, will have an audio component. The grid, therefore, has a radio frequency voltage, an audio voltage, and a direct current voltage applied to it. The direct current voltage serves as a bias for the tube. The radio frequency voltage and audio voltage are amplified in the tube, and appear across the impedances in the plate and screen circuits. The plate tank consisting of L2 and stray capacities 55 has appreciable impedance only at the radio frequency, so only the radio frequency voltage appears across it. The resistor 13 is bypassed for radio frequency so only the audio voltage appears across it. When an amplitude modulated radio 60 frequency voltage is applied to a grid-leak detector, the grid circuit acts exactly as a diode detector thereby resulting in the detected audio voltage being present between grid and cathode of the tube. This voltage is amplified by the 65 tube, and appears in the plate circuit. The entire process is called grid-leak detection.

In practice, the major portion of the tuning capacity for coil L1 is contributed by stray capacitances, and especially that of the leads from the oscillator section to the pickup path. Merely by way of illustration, it is pointed out that in an average pickup the capacity between 70 pickup electrodes is about 0.25 mmf., while the capacity between wires is of the order of 10 mmf.

At coil L2 the stray capacity of the wiring must be considered part of the tuning capacity.

It is pointed out, furthermore, that either of the fixed electrodes 1 or 2 may be removed thereby to provide single-sided operation. If the associated wire is removed, a fixed capacitor should replace the stray capacities which would be absent. In the case of single-sided operation the general operation will be the same, except that the variations in phase and magnitude of the high frequency voltage across coil L2 will not be as great as in the case of push-pull operation.

While I have indicated and described a system for carrying my invention into effect, it will be apparent to one skilled in the art that my invention is by no means limited to the particular organization shown and described, but that many modifications may be made without departing from the scope of my invention.

What I claim is:

1. In combination, a tube provided with an oscillator section and an output electrode, means connected to said oscillator section to provide angle modulated oscillations which have a predetermined mean frequency, a resonant circuit coupled to said output electrode, electron coupling between said oscillator section and said output electrode developing said angle modulated oscillations in the circuit connected to said output electrode, said resonant circuit being tuned to a frequency different from said mean frequency by a predetermined value, means responsive to operation of said first-named means for providing frequency changes at the output electrode resonant circuit, a feedback coupling from the resonant output circuit to said oscillator section, and resistive means in circuit with the output electrode for developing a voltage representative of the said angle modulation.

2. In combination, a tube provided with an oscillator section and a positive output electrode, transducer means connected to said oscillator section to provide frequency modulated oscillations which have a predetermined mean frequency, a resonant circuit coupled to said output electrode, electron coupling between said oscillator section and said output electrode developing oscillations in the circuit connected to said output electrode, said resonant circuit being tuned to a frequency different from said mean frequency, a second transducer means responsive to operation of said first-named transducer means for providing changes in tuning of said resonant output circuit, a capacity feedback path coupling the output electrode to said oscillator section, and an audio frequency voltage output resistor in circuit with the output electrode.

3. In combination, a tube provided with an oscillator section and an output electrode, means connected to said oscillator section to provide modulated oscillations which have a predetermined mean frequency, a resonant circuit coupled to said output electrode, coupling between said oscillator section and said output electrode developing said modulated oscillations in the circuit connected to said output electrode, means responsive to operation of said first-named means for providing frequency changes at the output electrode resonant circuit, a feedback path from the resonant output circuit to said oscillator section, and means in circuit with the output electrode for developing a voltage representative of the said modulation.

4. In combination, a tube provided with an oscillator section and a positive output electrode,

transducer means connected to said oscillator section to provide frequency modulated oscillations which have a predetermined mean frequency, a resonant circuit coupled to said output electrode, coupling between said oscillator section and said output electrode for developing oscillations in the circuit connected to said output electrode, a feedback path coupling the output electrode to said oscillator section, and an audio frequency output resistor in circuit with the output electrode.

5. In a sound record reproducer system, a tube provided with an oscillator section and an output electrode, means connected to said oscillator section to provide angle modulated oscillations which have a predetermined mean frequency, a resonant circuit coupled to said output electrode, electron coupling between said oscillator section and said output electrode for developing said angle modulated oscillations in the circuit connected to said output electrode, said resonant circuit being tuned to a frequency different from said mean frequency by a predetermined value, a feedback coupling from the resonant output circuit to said oscillator section, grid-leak detection means in circuit with the oscillator section grid, and resistive means in circuit with the output electrode for developing a voltage representative of the said modulation.

6. In combination in a reproducer of sound records, a tube provided with an oscillator section and a positive output electrode, capacity pickup means connected to said oscillator section to provide frequency modulated oscillations which have a predetermined mean frequency, a resonant circuit coupled to said output electrode, electron coupling between said oscillator section and said output electrode for developing oscillations in the circuit connected to said output electrode, said resonant circuit being tuned to a frequency different from said mean frequency, a second capacity pickup means responsive to operation of said first-named pickup means for providing changes in tuning of said resonant output circuit, a capacity feedback path coupling the output 45 electrode to said oscillator section, and an audio

frequency output resistor in circuit with the output electrode.

7. In combination, in a system for reproducing records, a tube provided with an oscillator section 5 and an output electrode, said oscillator section having a grid and anode electrode, means connected to said oscillator section grid to provide frequency modulated oscillations which have a predetermined mean frequency, a resonant circuit coupled to said output electrode, electron coupling between said oscillator section and said output electrode for developing said frequency modulated oscillations in the circuit connected to said output electrode, said resonant circuit being tuned to a frequency different from said mean frequency by a predetermined value, means responsive to operation of said first-named means for providing frequency changes at the output electrode resonant circuit, a feedback coupling 15 from the resonant output circuit to said oscillator grid, grid leak detection means in circuit with said oscillator grid, and resistive means in circuit with the output electrode resonant circuit for developing an audio frequency voltage representative of the said modulation.

8. In combination, a tube provided with an oscillator section and a positive output electrode, a first capacity pickup device connected to said oscillator section to provide frequency modulated oscillations which have a predetermined mean frequency of the order of 26 megacycles, a resonant circuit coupled to said output electrode, electron coupling between said oscillator section and said output electrode developing oscillations in the circuit connected to said output electrode, said resonant circuit being tuned to a frequency of the order of 26.1 megacycles, a second capacity pickup device responsive to operation of said first-named pickup device for providing opposite changes in tuning of resonant output circuit, a capacity feedback path coupling the output electrode to said oscillator section, and an audio frequency output resistor in circuit with the output electrode.

HARRY J. WOLL.
